BRAKE HANGER RETAINING MEANS

Filed Jan. 31, 1936

UNITED STATES PATENT OFFICE

2,083,784

BRAKE HANGER RETAINING MEANS

Victor H. Harbert, Chicago, Ill., assignor to Illinois Railway Equipment Company, Chicago, Ill., a corporation of Illinois

Application January 31, 1936, Serial No. 61,767

4 Claims. (Cl. 188—209)

My invention relates to means for retaining and suspending the hangers of brakes of railroad cars from the truck frames; the invention having for its object the provision of means whereby the links, whether of a continuous or U-shape form, although more especially adapted for use with the link type of hanger, are securely and pendently held in place against improper vibration and chatter, while at the same time permit 5 the ready removal and substitution of either type of link without necessitating alteration in the socket or pocket formed in the bracket arm secured to the truck frame.

My invention has for one of its objects the provision of hanger retaining members or blocks so formed that vibratory or twisting movement of one block on the other will be prevented and consequently also a frictional relation between the members or blocks and the walls of the socket 20 in the bracket arm eliminated.

The objects and the advantages of my invention will all be readily comprehended from the following detailed description of the accompanying drawing wherein:

25 Figure 1 is a side elevation of a portion of truck frame and bracket provided with my improved retaining means, with the portions of the brake hanger broken away and shown in section.

Figure 2 is a view taken at right angles to Figure 1 and looking at the forward side of the bracket and my improved retaining means, intermediate portions of the bracket and of the brake hanger being broken away.

Figure 3 is a sectional elevation taken substantially on the line 3—3 of Figure 2.

Figure 4 is a transverse sectional view taken substantially on the line 4—4 of Figure 3.

Figure 5 is a perspective view of the two members or blocks, which constitute the hanger retaining means, in position to be fitted about the upper end of the brake supporting hanger.

My improved retaining means is especially intended for use in connection with the continuous or closed link type of hanger illustrated at 10; and the hanger or link retainer means are intended to be used more especially with the open sided bracket shown at 11 in Figure 2.

The bracket is preferably integral with the truck frame 12 at a point adjacent to the wheels, with the outer end provided with vertically spaced apart portions 13, 13 united at the rear and thus providing an open front and side pocket. The bracket is of the well known type as more clearly disclosed in my former Patent Number

1,734,088 and hence will need no further detailed description.

The link hanger retaining means or keeper elements are shown at 14, 14, in Figure 5; a pair of keeper elements being used, one on top of the other, and the two elements with the upper end of the link hanger disposed therebetween, are then inserted through the forward open end of the pocket formed in the bracket.

The keeper elements 14, 14 are identical in construction, with the matching or abutting faces provided with a dished portion or arcuate groove 15, extending longitudinally from end to end of each element or block 14. The grooves 15 of the two elements or blocks when the latter are 15 in superposed relation constitute a substantially circular channel adapted to swingingly support the upper closed end of the brake hanger 10.

The rear longitudinal sides of the keeper elements 14, namely the sides which extend into the rear of the pocket in the bracket, are preferably shouldered as shown at 16 intermediate of the ends of the keeper elements as clearly shown in Figure 5; the shoulders 16 fitting into the rear portion of the pocket; while the ends of the keeper elements adjacent the shoulders are preferably rounded as shown at 17 to seat on the curved partial end walls 18 of the pocket.

With the shoulders 16 of the keeper elements extending into the pocket rearward of the forward faces of the end walls 18 of the pocket, longitudinal movement of the superposed keeper elements in the pocket is impossible and proper positioning in the bracket maintained.

The keeper elements or blocks 14, being identical in construction, are interchangeable and permit either element or block to be located above or below the hanger. As a result, easy assembly is not only made possible, but a comparatively low cost of manufacture is provided.

In the particular design of keeper elements, the forward longitudinal sides of the blocks 14 are each shown provided with a vertically disposed arcuate groove 19 extending across the front face of each block to provide passage of a suitable bolt, as at 20, which is inserted through registering holes provided in the forwardly presented portions of the vertically spaced top and bottom walls 13 of the pocket in the bracket. With the bolt 20 seated in the sockets or grooves 19 and with the shoulders 16 extending rearwardly beyond the arcuate side walls 18 of the pocket, it is apparent that the superposed keeper elements with the hanger 10 will be held in the pocket of the bracket; and as the top and bottom walls 13 of 55

the pocket are preferably made to slope downwardly toward the rear, see Figures 1 and 3, practically no strains will be placed on the retaining bolt 20.

5 While the lower end of the bolt is usually threaded and provided with nuts as shown, it may be preferred to employ a suitable bolt locking means as at 21 in order to prevent accidental loss of the bolt in the event that the nuts should work 10 loose. The bolt lock shown is of well known construction and therefore will need no detailed description.

15 As the brake hanger is subjected to constant vibration and oscillatory movement, it is apparent that the keeper elements or hanger supporting and holding blocks 14, 14 will also be subjected to considerable vibration and twisting strains which will cause contacting surfaces to become worn.

20 In order to overcome this condition and prevent movement of one element or holding block on the other, I provide the opposing faces of the two blocks with interengaging or matching surfaces. These interengaging surfaces in the 25 specific embodiment consist of lugs and sockets so arranged that the lugs of one block will register with the sockets of the other block. For example, the flat face or wall on one side of the hanger receiving groove or channel is provided 30 adjacent one end with an upstanding and preferably slightly tapered lug 22, and at the other end of said face is provided with a matching hole or socket 23; while the flat surface on the opposite side of the groove or channel 15 of each block is 35 slightly enlarged intermediate of the ends and each provided with a lug 24 and a hole or socket 25 arranged preferably adjacent the lug 24.

40 It is apparent that when the blocks are arranged in superposed relation, causing the top block to be turned end for end as shown in Figure 5, the lug 22 at the right hand end of the lower block will register with and enter socket 23 at the right hand end of the upper block; the lug 22 at the left hand end of the upper block in 45 Figure 5 will register with the socket 23 at the left hand end of the lower block; while the lug 24 of the lower block will register with socket 25 in the upper block and its lug 24 will register with the socket 25 in the lower block.

50 With the multiple interlock between the two hanger retaining elements, it is apparent that shifting of one block on the other will be impossible and frictional or binding contact with associated surfaces or elements will be eliminated 55 and free oscillatory movement of the hanger or link 10 will be permitted.

In assembling the parts, the upper end of the hanger or link 10 is first placed in the groove 15 of the lower block, with the side of the block provided with the shoulder 16 and lug and socket 24, 25 disposed toward the pocket in the bracket; the upper block 14 is then placed on top of the lower block with its shouldered side also dis-

posed toward the pocket in the bracket. The lugs and sockets will thus all register and provide interlocking relation between the blocks which, together with the suspended hanger, are then inserted through the front opening of the pocket 5 with the vertical grooves 19 in the front sides of the blocks made to register with the bolt receiving holes in the upper and lower walls 13 of the pocket and the bolt 20 is then put into place.

10 While it may be possible to somewhat modify the construction shown, I believe the structure disclosed to be the best embodiment of my invention because merely a single pattern is necessary and hence low cost of manufacture provided; certain modifications being possible without departing from the spirit of my invention.

15 What I claim is:

1. Brake hanger retaining means of the character described comprising a pair of correlated members provided with matching faces adapted 20 to be superposed on each other, each member having a hanger receiving groove extending from end to end and each member having upstanding and depressed surfaces arranged at corresponding points, the depressed surfaces matching and 25 adapted to receive the corresponding upstanding surfaces, whereby the one member is locked against shifting movement on the other member.

2. Brake hanger retaining means of the character described comprising a pair of correlated 30 blocks, each block being provided with a hanger receiving groove extending from end to end and a flat seating surface on opposite sides of the groove, each of said surfaces being provided with a lug and a socket, the sockets of one block 35 matching and receiving the lugs of the other block whereby shifting movement between the blocks is prevented.

3. Brake hanger retaining means of the character described comprising a pair of matching 40 blocks adapted to be arranged in superposed relation with one end of a hanger therebetween, each block having a hanger receiving semi-cylindrical groove extending from end to end and having flat seating surfaces on opposite sides of the 45 groove, one longitudinal side of each block being formed for the vertical passage of a retaining bolt, the upper flat face of said side being provided with a socket at one end and an upstanding lug at the other end, while the upper flat face of the other longitudinal side has a socket and an upstanding lug adjacent each other intermediate of the ends of the blocks.

4. Brake hanger retaining means of the character described comprising a two part hanger retainer, each part being provided with a hanger receiving groove extending from end to end, the two parts being interchangeable and adapted to rest on each other in superposed relation and provided with interlocking surfaces at the longitudinal sides thereof whereby the two parts are held against shifting movement on each other.

55 60 65 VICTOR H. HARBERT.
